UNITED STATES PATENT OFFICE.

HAROLD ROBINSON WELLMAN, OF NEW YORK, N. Y., ASSIGNOR TO GENERAL INCANDESCENT ARC LIGHT COMPANY, OF NEW YORK, A CORPORATION.

MOTOR FOR DRIVING SEWING-MACHINES.

SPECIFICATION forming part of Letters Patent No. 690,384, dated December 31, 1901.

Application filed June 6, 1901. Serial No. 63,482. (No model.)

To all whom it may concern:

Be it known that I, HAROLD ROBINSON WELLMAN, a citizen of the United States, residing at New York city, county and State of New York, have invented certain new and useful Improvements in Motors for Driving Sewing-Machines or other Similar Apparatus, of which the following is a specification.

My invention relates to the construction and mounting of an electric motor designed for driving sewing-machines or other similar apparatus.

The object of my invention is a construction by means of which, through the medium of a foot-treadle, the motor may be thrown into and out of operation and different speeds of movement imparted to the driven machine at the will of the operator.

The accompanying drawings will serve to illustrate my invention, in which—

Figure 1 is a side elevation of a motor mounted upon a table in proximity to the machine to be driven and also illustrates the mounting, foot-treadle, and the connecting mechanism. Fig. 2 is an end view looking from the left. Fig. 3 is a top view showing the relation between the wheel to be driven and the driving-wheel and indicating in dotted lines the lateral movement of the driving-wheel relative to the driven wheel. Fig. 4 is a side elevation and vertical section taken on the line X X of Fig. 1.

In the drawings, 5 represents a table, such as is commonly used with sewing-machines and other similar apparatus. Mounted upon this table is a machine to be driven, such as a sewing-machine, (not shown,) and carrying a driving-wheel 6, which in the present case is supposed to be arranged transversely of the longitudinal axis of the table. Mounted upon and secured to the table by means of the clamp 7 is an electric motor 8. The motor is provided with the usual armature, (not shown), and on the inner end of the armature 45 is mounted a disk-wheel 9, whose longitudinal axis corresponds to that of the table—i. e., at right angles to the longitudinal axis of the wheel 6. The face of the wheel 9 is formed of a plate of leather 10 or other suitable resilient material which will have a frictional relation with the periphery of the wheel 6.

The motor 8 is adjustably mounted in the bifurcated standard 11, which standard has a pivotal bearing upon the horizontal pin 12, fixed in the standards 13 13^a on the upper portion of the clamp 7. Secured to the standard 13^a by the screw 14 is a plate 15, in which is formed the arc-shaped slot 16.

17 indicates a screw located in the slot 16 and secured in the standard 11. Surrounding the pin 12 is a helical spring 18, secured at one end to the standard 13 and at the opposite end to the screw 17.

It will be understood from the description so far as described that the motor 8 has a pivotal movement on the pin 12 and that this movement is limited to the length of the arc-shaped slot 16, and, further, that by reason of the action of the spring 18 the motor will normally occupy the position shown in Fig. 7^a—i. e., with the screw 17 toward the right-hand end of the slot 16. The purpose of this arrangement will hereinafter be described.

Pivoted on the right-hand end of the pin 12 is a bell-crank lever 19, Fig. 4. 75 The horizontal arm 19^a of this lever is pivotally connected to the adjustable rod 20, which is connected at its lower end to the foot-treadle 21. The vertical end 19^b of the lever 19 has secured to it a rectangular plate 22, preferably formed of insulating material and carrying on its inner side a metal plate 23.

Mounted upon the standard 11 and insulated from the standard are the contacts 24, connected to conductors 25, which lead to the interior of the motor-case. With the parts in the position shown in Fig. 4 the plate 23 bridges the contacts 24 and serves to close the circuit between them.

26 represents conductors leading from the source of energy to and from the motor.

The operation of my device is as follows: Normally the parts will occupy the position shown in Figs. 1, 2, and 3 of the drawings. When the foot-treadle is depressed, the bell-crank lever 19 is drawn down, the effect of which is first to bring the plate 23 in contact with the contacts 24, Fig. 4, and close the circuit through the motor. As the lever is further depressed the motor and its standard are tilted to the left. This causes the disk wheel 9 to move across the edge of the driven wheel

6, with the result that motion is transmitted to the driven wheel. The speed of movement, it will be understood, will depend upon the degree to which the motor is tilted until the limit of the slot 16 is reached.

5 In this specification I have described the motor as mounted upon a pivoted support and oscillating relative to the driven device. Manifestly the motor may be otherwise mounted and move so as to transmit different speeds to the driven device.

10 Having thus described my invention, I claim—

1. In combination with a driven wheel, a 15 horizontally-pivoted motor device carrying a driving-wheel in frictional relation with and disposed at right angles to the driven wheel, and means for varying the speed of rotation of the driven wheel.

20 2. In combination with a driven wheel, a horizontally-pivoted motor device carrying a driving-wheel in frictional relation with and disposed at right angles to the driven wheel, and means for moving the driving-wheel 25 across the periphery of the driven wheel.

3. In combination with a driven wheel, a horizontally-pivoted motor device carrying a driving-wheel in frictional relation with and disposed at right angles to the driven wheel, 30 means for establishing an electric circuit through the motor, and means for moving the driving-wheel across the periphery of the driven wheel.

4. In combination with a driven wheel, a 35 horizontally-pivoted motor device carrying a driving-wheel in frictional relation with and disposed at right angles to the driven wheel, a foot-treadle, and means interposed between the foot-treadle and the motor device for establishing an electric circuit through the motor and causing the driving-wheel carried by the motor to be moved across the periphery of the driven wheel.

5. In combination with the driven wheel, a 45 horizontally-pivoted motor device carrying a driving-wheel, a body of frictional material mounted on the face of the driving-wheel and in contact with the periphery of the driven wheel, and means for causing the driving-wheel to move across the periphery of the driven wheel.

6. In combination with an electric motor carrying a driving-wheel, a supporting-standard in which said motor device is vertically 55 adjustable, a support for said standard, and a clamping device for securing said support to a table or other body.

7. In combination with an electric-motor de-

vice carrying a driving-wheel, a support for said motor, means for effecting movement of 60 said motor device in an arc of a circle relative to the driven device, and means for limiting the degree of movement of the motor device.

8. In combination with an electric-motor de- 65 vice carrying a driving-wheel, a support for said motor, a resilient device for maintaining the original position of the motor, means for moving the motor and its support, and means for limiting the movement of the motor and 70 its support.

9. In combination with an electric motor carrying a driving-wheel, a horizontally-pivoted support for said motor carrying electric contacts, and means for moving the motor and 75 its support, and for closing the circuit through said contacts.

10. The combination of an electric motor carrying a driving-wheel, a support therefor, a clamping-standard, a pin carried in said standard, and on which said support for the motor is mounted, a slotted plate connected to said support for limiting the degree of oscillation of the motor, a bell-crank lever mounted on said pin, and a foot-treadle connected to the bell-crank. 85

11. The combination with an electric motor carrying a driving-wheel, a support for said motor carrying electric contacts, a pivoted bell-crank carrying contacts in circuit with a 90 source of electric energy, means for moving said bell-crank to close circuits through the motor and for moving the motor and its support.

12. The combination with an electric motor 95 carrying a driving-wheel, a pivotal support for said motor carrying electric contacts, a pivoted bell-crank carrying contacts in circuit with a source of electric energy, means for oscillating the bell-crank and closing the 100 circuit between the contacts on the motor-support and bell-crank, and means for oscillating the motor and its support.

13. In combination with a driven wheel, a horizontally-pivoted motor device carrying a 105 driving-wheel in frictional relation with and disposed at right angles to the driven wheel, and means for oscillating the motor device upon its support.

In testimony whereof I affix my signature 110 in the presence of two witnesses.

HAROLD ROBINSON WELLMAN.
